CLAIM

The ornamental design for a shoe outsole bottom, as shown and described.

DESCRIPTION

FIG. 1 is a perspective view of a shoe outsole bottom in accordance with my new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a rear elevation view thereof; and,

FIG. 7 is a front elevation view thereof.

The broken lines shown in the drawings represent portions of the shoe upper, midsole periphery and outsole bottom that form no part of the claimed design. The dot-dash broken lines define the bounds of the claimed design and form no part thereof. The surfaces devoid of shading lines are not claimed. The faded portions for FIGS. 8, 9, 10, 14, and 15 do not form any of the claimed design.
